UNITED STATES PATENT OFFICE.

LALLIE ZERGA, OF PHILADELPHIA, PENNSYLVANIA, ASSIGNOR OF ONE-HALF TO
H. J. ROSEGRANT, OF PHILADELPHIA, PENNSYLVANIA.

HEALTH-SHOE.

1,173,696.

Specification of Letters Patent. Patented Feb. 29, 1916.

Application filed April 8, 1915. Serial No. 19,853.

To all whom it may concern:

Be it known that I, LALLIE ZERGA, a citizen of the United States, residing at Philadelphia, in the county of Philadelphia and State of Pennsylvania, have invented new and useful Improvements in Health-Shoes, of which the following is a specification.

My invention relates to new and useful improvements in health shoes, and has for its object to provide an exceedingly simple and effective device of this character, whereby the arch of the foot upon which the shoe is placed will be held in place in its natural position, and will provide an easy and flexible support thereof, and having sufficient elasticity to give with the spreading of the foot when the weight of the body is brought to bear thereon.

A still further object of the invention is to provide a shoe of the class described embodying an arch support having sufficient flexibility to conform to the different shapes of the foot, and which will not cause the wearer pain or inconvenience.

With these ends in view, this invention consists in the details of construction and combination of elements hereinafter set forth and then specifically designated by the claims.

In order that those skilled in the art to which this invention appertains may understand how to make and use the same, I will describe its construction in detail, referring by numeral to the accompanying drawing forming a part of this application, in which—

Figure 1, is a side elevation of a shoe made in accordance with my improvement, showing by dotted lines the position of the arch support and the ordinary counter. Fig. 2, is a similar view showing a slightly modified form of my invention, a portion of the leather and the outer lining being broken away to plainly illustrate the construction of my improved shoe. Fig. 3, is a section at the line 3—3 of Fig. 1; and Fig. 4, is a section at the line 4—4 of Fig. 2, a portion of the shoe being broken away.

The gist of my invention consists in producing a shoe having integral therewith a flexible arch support which is placed in position during the manufacture of the shoe, and is situated between the upper and lining

of the inside portion of the shoe in the region of the arch.

In carrying out my invention as here embodied 2 represents a shoe constructed in the ordinary manner and comprising a sole 3, vamp 4, upper 5, counter 6, outer lining 7 and inner lining 8.

In that form of my invention as illustrated in Figs. 1 and 3 I place an elastic arch support 9 between the inner lining 8 and the vamp 4, or between the inner and outer linings on the inside of the shoe, considered relatively to a pair of shoes when placed upon the feet, and the upper and lower ends or edges are secured to the sole and upper of the shoe at the same time the parts are fastened together, and preferably by stitching as indicated by the reference numeral 10. The two longitudinal edges of this support which are made from suitable elastic material are left free, and when being fastened in place is held under a slight tension or is slightly expanded. This supporter is positioned in the region of the arch and preferably overlaps a small portion of the counter 6 which is constructed in the ordinary manner from leather or other suitable and similar material. The supporter when formed from elastic material and attached to the upper of the shoe at two opposite ends of the supporter has a tendency to draw the points where it is attached, toward each other, but when the shoe is fastened upon the foot, this action causes the shoe to snugly fit the foot in the region of the arch, thereby properly supporting the foot at the weakest point, preventing undue strain thereon and properly holding it in its natural position, but permitting the free movement or spreading of the foot while walking, so that the wearer will feel no ill effects.

By the use of my improvement, the exceedingly hard and stiff counters and metallic braces are entirely eliminated, and as is well known the rigidity of such devices is very harmful to the feet, and often causes more ill than good effects.

In Figs. 2 and 4, the supporter is of greater length than that illustrated in the other figures, and runs from the sole to the instep of the shoe, this upper end which terminates at the instep being secured to the upper of the shoe by the same stitching

11 which attaches the button hole strip 12 to the upper. In this form of the device the supporter not only assists the arch of the foot to assume its natural position, but 5 also causes the ligaments of the arch to be held in their natural position, gently but firmly holding the arch and instep to prevent sagging, breaking or other deformities in the region of the arch of the foot.

10 It will be seen that the construction of my device does away with casings, covers, in-soles or other objectionable elements which are generally used in manufacturing arch supporters, and the supporter does not 15 run entirely around the foot which is objectionable to the wearer. The supporter is less likely to wear out or deteriorate because of its situation or position in the shoe, there are no unsightly protuberances, and 20 it is not separate from the shoe therefore not making it difficult to place upon the foot. In fact, a shoe made with my improvement has all the appearances of the ordinary shoe.

25 Of course I do not wish to be limited to the exact details of construction as herein shown, as these may be varied within the limits of the appended claims without departing from the spirit of my invention.

30 Having thus fully described my invention, what I claim as new and useful, is—

1. As an article of manufacture a shoe, and an arch support forming a part thereof, said arch support consisting of an elastic band secured under tension at its upper and lower ends to portions of the shoe in the region of the arch.
2. As an article of manufacture a shoe, and an arch support forming a part thereof, 40 said arch support consisting of an elastic band secured under tension at its upper and lower ends to portions of the shoe in the region of the arch and on the inside portion thereof, considered relatively to a pair of shoes.
3. A health shoe comprising a sole, a vamped upper, and a strip of elastic material adapted to act as an arch support

secured under tension to the points of connection of the sole with the vamp and the 50 vamped upper.

4. A health shoe comprising a sole, a vamped upper, and a strip of elastic material adapted to act as an arch support secured under tension at its lower and upper edges at the points of the connection of the sole with the vamp and the vamped 55 upper, in the region of the arch.

5. A health shoe comprising a sole, a vamped upper, and a strip of elastic material adapted to act as an arch support secured under tension at its lower and upper edges at the points of the connection of the sole with the vamp and the vamped 60 upper, in the region of the arch, 65 the two opposite remaining edges being free.

6. A health shoe comprising a sole, a vamped upper, and an elastic strip adapted to act as an arch support situated in the 70 region of the instep on the inside portion of the shoe, having its upper end secured thereto in the region of the instep and its lower end secured to the shoe at the point of connection between the vamp and sole. 75

7. A health shoe comprising a shoe of ordinary construction having an elastic band secured under a slight tension on the inside portion of the shoe between the linings at the point of connection between the 80 sole and vamp and vamped upper.

8. A health shoe comprising a shoe of ordinary construction having an elastic band secured under a slight tension on the inside portion of the shoe between the linings at the point of connection between the sole and the vamp and the upper and button hole strip. 85

In testimony whereof, I have hereunto affixed my signature in the presence of two 90 subscribing witnesses.

LALLIE ZERGA.
